COMBINED MONEY COUNTER AND WRAPPER

Gerald J. Bryant, 3170 Ocean Beach, Longview, Wash.

Filed May 29, 1961, Ser. No. 65,395

Term of patent 14 years

(Cl. D52—4)

Fig. 1

Fig. 3

Fig. 2

FIGURE 1 is a perspective view showing my new design for a combined money counter and wrapper;

FIGURE 2 is a front elevational view; and

FIGURE 3 is a cross-sectional view taken along line 3-3 of FIGURE 2, as viewed in the direction of the arrows.

The wrapper shown in broken lines in FIG. 3 is for illustrative purpose only.

I claim:

The ornamental design of a combined money counter and wrapper, as shown and described.
